Primary Examiner — Mehri F Bajoul

(57) **CLAIM**

The ornamental design for a flying disc game target, as shown and described.

DESCRIPTION

FIG. 1 is a front view of a flying disc game target showing my new design;

FIG. 2 is a rear view of the flying disc game target;

FIG. 3 is a right side view of the flying disc game target;

FIG. 4 is a left side view of the flying disc game target;

FIG. 5 is a top view of the flying disc game target;

FIG. 6 is a bottom view of the flying disc game target; and, FIG. 7 is a top front side perspective view of the flying disc game target.

The dash-dot-dot broken lines are illustrative of portions of the flying disc game target forming no part of the claimed design. The dash-dot broken lines are illustrative of netting forming part of the claimed design.

1 Claim, 7 Drawing Sheets
